PHOTOGRAPH ALBUM

Roy E. Orvedahl, Minneapolis, Minn.

Application November 3, 1951, Serial No. 17,259

Term of patent 3½ years

(Cl. D6—2)

To all whom it may concern:

Be it known that I, Roy E. Orvedahl, a citizen of the United States of America, residing at 6713 13th Avenue South, city of Minneapolis, county of Hennepin, State of Minnesota, whose post-office address is 6713 13th Avenue South, Minneapolis, Minnesota, have invented a new, original, and ornamental Design for a Photograph Album, of which the following is a specification, reference being had to the accompanying drawing, forming a part thereof, and in which:

Fig. 1 is a front elevational view of a photograph album, showing my new design;

Fig. 2 is a top plan view of the same;

Fig. 3 is a rear end elevational view of the same; and

Fig. 4 is a front end elevational view of the same.

The back side of the embodiment shown in Figs. 1, 2, 3 and 4 is plain.

I claim:

The ornamental design for a photograph album, substantially as shown and described.

ROY E. ORVEDAHL.
